UNITED STATES PATENT OFFICE.

WILLIAM C. JURGENS, OF OAKLAND, CALIFORNIA.

DESIGN FOR A SERVING-TRAY WARMER.

58,029.

Specification for Design.

Patented May 31, 1921.

Application filed July 19, 1920. Serial No. 397,506. Term of patent 14 years.

To all whom it may concern:

Be it known that I, WILLIAM C. JURGENS, a citizen of the United States, residing at Oakland, in the county of Alameda and State of California, have invented a new, original, and ornamental Design for Serving-Tray Warmers, of which the following is a specification, reference being had to the accompanying drawing, forming part thereof.

Figure 1 is a plan view of my serving tray warmer.

Fig. 2 is a side elevation of the same.

Fig. 3 is a perspective view of my serving tray.

I claim:

The ornamental design for a serving tray warmer.

In testimony whereof I affix my signature.

WILLIAM C. JURGENS.
